(57) **CLAIM**

The ornamental design for a wall-mount support, as shown and described.

DESCRIPTION

FIG. 1 is a front-left perspective view of a wall-mount support showing the claimed design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The dashed broken lines of FIGS. 1-7 represent boundaries of the design; the dashed broken lines themselves and the areas within form no part of the claimed design.

1 Claim, 5 Drawing Sheets

FIG. 1

FIG. 2

FIG. 3

FIG. 4

FIG. 5

FIG. 6

FIG. 7
